UNITED STATES PATENT OFFICE

2,037,810

CONTROL DEVICE

Harold A. Mantz, Milwaukee, Wis., assignor to
Milwaukee Gas Specialty Company, Milwaukee,
Wis., a corporation of Wisconsin

Application October 2, 1931, Serial No. 566,395

19 Claims. (Cl. 158—117.1)

My invention relates to heating devices and particularly to control means for controlling the flow of, and igniting of the fuel for, such heating devices.

In heating appliances, such as gas heaters, it is very desirable that gas issuing from the burner be ignited as soon as it begins to flow, otherwise a considerable volume of gas may flow from the burner and a severe explosion occur when the 10 gas is ignited. If ignition by the ignition device does not occur gas may collect in such quantities as to result in a disastrous explosion by ignition from some outside source or, if no ignition occurs, then asphyxiation of anyone in the room where 15 the heater is located.

I have conceived of a control means which will prevent the flow of gas to the burner unless the ignition device is in operation. My control device 20 preferably employs a bleeder mechanism for controlling the flow of gas to the burner and a feature of my invention is that the gas issuing from the bleeder system is burned in a position where the burning gas assists the ignition system. Another 25 feature of my invention is that the gas from the ignition system and from the bleeder system is burned at a location where the heating effect is usefully employed. Still another feature of my invention is that the bleeder flame burns only 30 when the heater is not in operation and therefore is of assistance to the ignition system at a time when it is most useful.

An object of my invention is to provide a control system for controlling the flow and ignition of fluid fuel for a heating system.

35 More particularly it is an object of my invention to provide a control system which will prevent the flow of gas into and from the burner of a heating system unless an ignition device is in operation.

40 Another object of my invention is to provide, in a system utilizing a bleeder system, means for burning all of the fuel used for ignition and bleeding purposes at one point.

Another object of my invention is to provide, in 45 a system of the above character, a bleeder system in which gas or other fuel is burned only when the heater is not in operation.

Still another object of my invention is to provide, in 50 simple, reliable and effective, and which is inexpensive to manufacture, install and maintain.

Other and further features and objects of the 55 invention will be more apparent to those skilled in the art upon a consideration of the accompanying drawing and the following specification,

wherein is disclosed a single, exemplary embodiment of the invention, with the understanding, however, that such changes may be made therein as fall within the scope of the appended claims without departing from the spirit of the invention.

In said drawing:

Figure 1 is a schematic representation of the various parts of my control system in their relative positions, together with the connections employed for conducting fuel to and from the various devices.

Figure 2 is an enlarged view partly in section and partly in elevation of the pilot burner, the bleeder burner and a portion of the heater burner shown in Figure 1; and

Figure 3 is an enlarged view in vertical section of the valve mechanism and conduits shown in connection with the pilot burner in Figure 1.

The embodiment of the invention shown and described is particularly suitable for use with gas heaters, but it is quite apparent that the system may be used or modified for use with other fuels and in other heating and control systems.

Referring now to the drawing for a more complete disclosure of this invention there is shown at 10 a conduit or manifold for supplying gas to the system including the heater burners 11 and 11a, the bleeder burner conduit 12 and the pilot burners 13 and 13a. The flow of gas into the 30 manifold 10 is controlled by a manually operable valve 14.

The inlet chamber 16 of a diaphragm valve 17 is connected to the manifold 10 and an outlet chamber 18 of the valve 17 is connected by means 35 of the conduit 19 to the valves 21 and 21a of burners 11 and 11a, respectively.

The wall 22 in the diaphragm valve body 23 between the inlet and outlet chambers is provided with a circular opening 24 and a valve 26 is adapted to close the opening.

A diaphragm housing 27 comprised of two shallow, cooperating plate-like members 28 and 29, is disposed on the top of the valve body 23. A relatively large circular diaphragm 31 is clamped 45 between the two members of the diaphragm housing as by means of bolts 30 and, since the diaphragm is gas tight two chambers 32 and 33 are formed, one on each side of the diaphragm. A conduit 34 connects the inlet chamber 16 of the valve body 23 with the chamber 32 in the diaphragm housing.

A valve stem 36 is connected at its upper end to the diaphragm 31 and at its lower end to the valve 26 so that vertical movement of the dia- 55

phragm results in opening and closing of the valve 26. A spring 37 is provided within the valve body 23 and the spring bears against the upper portion of the valve body and against the valve 26 to normally maintain the valve in closed position. The diaphragm 31 is sufficiently large, however, that the gas pressure in chamber 32 of gas from the manifold 10 is sufficient to move the diaphragm upwardly to raise the valve 26 from its seat providing, of course, that the pressure within the chamber 33 is substantially at atmospheric pressure. The diaphragm valve itself constitutes no part of my present invention except in its connection with the system as a whole and therefore need not be further described at this time.

A conduit 41 leads from the manifold 10 to the bleeder valves 40 and 40a and to the pilot burners 13 and 13a. The pilot burner is comprised of a head 42 having a pair of vertically extending bores or channels 43 and 44 therein. The bore 44 is open to the atmosphere at its upper end and extends laterally to make connection with the bore 43. A vertically extending conduit 46 is connected by means of the bleeder valve body 47 with the conduit 41, and gas from the manifold 10 and the conduits 41 and 46 is admitted to the chamber within the pilot head formed by channels 43 and 44, through a jet 48 which is connected to the upper end of the conduit 46 by means of a spud 49. The pilot head 42 rests on a reduced portion of a spud. The channel 43 is provided with a Venturi bushing 51 so that gas issuing from the jet 48 passes through the Venturi bushing and carries air from the channel 44 with it.

The mixture of gas and air in the channel 43 is burned after it has passed out through suitable ports in the burner 52, to form a flame 53 which is suitable for ignition purposes. A hemispherical shield 54 is fastened on the end of the burner 52 in order to protect the flame from air currents and the like. A suitable opening is provided in the upper part of the shield 54 to permit the flame 53 to reach the thermostatic element 56. The thermostatic element 56 is preferably of U-shape with one arm secured to the top of the pilot head 42 as by means of a bolt 57 and with the other secured to a strip 58 as by means of rivets 59. An adjusting screw 61 is threaded into the end of the strip and may be locked with respect thereto by means of the nut 62.

A conduit 63 leads from the pilot burner supply conduit 41 to a temperature limit control device 64. The temperature limit control device may be of any desired construction but in the embodiment of the invention shown is comprised of a housing 66 in which a valve (not shown) is located, and a pair of rods 67 and 68 of different coefficients of expansion mounted on the housing, and engaged to the housing and the valve in the housing in such a manner that the valve is maintained in a closed condition until a certain preselected temperature is reached. The temperature limit control 64 is preferably placed above the heater or adjacent thereto or in a room heated by the heater so that it may be used to regulate the temperature of the room or other enclosed space. When the valve within the housing 66 is opened gas may flow from the conduit 63 into the conduit 69 and into the chamber 33 of the diaphragm valve by means of the conduit 71.

The valve housing 40 is preferably located below the pilot head 42 and is preferably provided with two vertically extending channels 72 and 73 and a laterally extending connecting channel 74.

The conduit 41 is threaded into the valve body 47 to communicate with the channel 72 and the transverse channel 74. The conduit 46 is threaded into the valve body 47 at a position opposite to the conduit 41 and also communicates with the channels 72 and 74. An elongated bushing 76 is threaded into the uppermost portion of the valve body 47 in the channel 73, in side by side relation with the conduit 46, and into the bottom part of the pilot head 42. The bushing 76 not only affords a means of holding the pilot head and valve body in spaced relation, but also furnishes a channel in which the push rod 77 is located. The push rod 77 passes through the bushing 76 and the pilot head 42 and rests against the adjusting screw 61 on strip 58. A bushing 78 is located within the valve body 47 in the channel 73. The bushing not only affords a guide for a valve stem 79 which is secured to the push rod 77, but also furnishes a valve seat 81 for the valve 82. The bushing 78 extends through the transverse channel 74 and is provided with transverse openings 83 to provide communication between the channel 74 and a vertically extending channel 84 in the bushing 78. The channel 73 is slightly enlarged just below the valve seat 81 to permit a free flow of gas through the channel. A conduit 86 is threaded into the valve body 47 at a position in which it affords communication with the channel 73. The conduit 86 is connected to a conduit 87, as by means of the fitting 88, and the conduit 87 to the conduit 71 to form a channel leading into the upper diaphragm-valve chamber 33.

It may readily be understood that, on opening valve 14, gas from the manifold 10 passes through the conduit 41 and into the chamber 74 in the valve body 47. A portion of the gas in the chamber 74 passes through the conduit 46, through the jet 48, and into the chamber 44 where it is mixed with air, through the Venturi bushing 51, and out through the burner 52. The other portion of the gas in the chamber 74 passes through the openings 83 in the bushing 78, through the channel 84, through the channel 73, through the conduits 86, 87 and 71, and into the chamber 33, so long as the valve 82 is in its open position. The valve 82 is normally held in open position by the thermostatic element 56, but a spring 88 located within the bushing 78 and bearing against an enlarged portion of the rod 77 is arranged to bias the valve 82 to a closed position as soon as the pressure imposed by the thermostatic element 56 is removed.

In operation of the heating system gas is admitted into the manifold 10 by opening the valve 14 and, since the conduit 41 is connected directly to the manifold 10, gas flows through the conduit 41 into the valve body 47, where the flow of gas is divided. A portion of the gas in the valve body 47 passes through the conduit 46 and into the pilot burner 13 where it forms the pilot flame 53. The other portion of the gas in the valve body 47 passes through the channel 73 and through the conduits 86, 87 and 71, into the chamber 33 in the diaphragm valve during the period in which the pilot flame is not ignited, and consequently the thermostat is in a position pressing downwardly upon the rod 77 to maintain the valve 82 in open position. This latter system may be termed an "indirect" means of supplying gas to the diaphragm valve. Since the conduit 34 of the diaphragm valve is connected to the inlet chamber 16 and to the chamber 32 in the diaphragm valve housing 18, gas is fed directly to the chamber 32 and the pressure of gas on both sides of the diaphragm 31 is substantially the same and the valve 76

26 does not open. Gas is bled slowly from the chamber 33 by means of the conduit 12. The gas flowing through the conduit 12 is burned in a pilot flame 51 which is located adjacent the pilot flame 53 and the quantity of gas flowing per unit of time is regulated by a needle or throttle valve 89. As long as the valve 82 is open the gas in the chamber 33 is replaced at a rate faster than it can be bled through the throttle valve 89 and conduit 12.

As soon as the thermostatic element is heated sufficiently by the flame 53 the arms of the thermostatic element spread to permit the rod 11 to move upwardly to a sufficient extent to permit the valve 82 to be closed by the spring 88. When the valve 82 has closed the supply of gas leading through the conduits 86, 87 and 71 to the chamber 33 in the diaphragm valve is cut off and the gas already in the chamber is bled through the conduit 12 and burned in the flame 51. The pressure in the chamber 32 is now greater than the pressure in the chamber 33 and the diaphragm moves upwardly to lift the valve 26 from its seat and permit the flow of gas through the valve 24 port 24 into the outlet chamber 18 and through the conduit 19 to the valves 21 and 21a which lead, respectively, to the burner 11 and 11a. When either one or both of the valves 21 and 21a are turned to the "on" position gas passes through the respective burners and is ignited by the ignition flame 53. Since gas is being bled out of the chamber 33 by means of the valve 89 and the conduit 12 and since no more gas is being supplied to the chamber the flame 51 finally dies out.

While the above operation is going on the temperature limit valve 64 is closed, but when the temperature of the oven or other enclosed space above the heater 11 reaches a predetermined value the valve 64 opens, permitting gas to flow from the conduit 63 into the conduit 69 and through the conduit 71 into the chamber 33. Since the pressure on each side of the diaphragm 31 is now equalized or substantially equalized, the diaphragm moves downwardly and the valve 26 closes to prevent the flow of gas into the burners 11 and 11a. When the temperature of the oven decreases to a sufficient extent the temperature limit valve 64 closes, the gas within the chamber 33 is bled off through the conduit 12 and the valve 26 is again opened to permit the flow of fuel to the burner 11 and 11a. The gas flowing from the burners is ignited by the pilot flame 53 and heating of the oven or other enclosed space is continued. If the pilot flame 53 should become extinguished the thermostatic element 56 cools and drives the rod 11 downwardly to open the valve 82 and permit the flow of fuel through the conduits 87 and 71 into the chamber 33, thus equalizing the pressure on both sides of the diaphragm and permitting the valve 26 to close under the influence of the spring 37 to prevent the flow of fuel to the heater burner.

It may readily be understood that I have provided a control system for controlling the flow of fuels which will prevent the flow of fuel to the burner or other device unless the ignition device is in operation, and that I have also provided a means of burning the bleeder gas with the pilot gas thereby preventing the escape of unburned gas from the system.

Although I have described a specific embodiment of my invention, it is apparent that modifications may be made by those skilled in the art. Such modifications may be made without depart-

ing from the spirit and scope of my invention as set forth in the appended claims.

I claim as my invention:—

1. In a fluid-fuel flow control system, a main fuel supply line including a main valve, means for controlling the main valve by fuel pressure, a pilot burner, a thermostatic element mounted on the pilot burner, a bleeder valve body, a bleeder valve within the valve body, a rod for transmitting motion of the thermostatic element to the valve, a continuous open fuel supply line for conveying fuel from the main line to the bleeder valve body, a conduit for conducting fuel from the bleeder valve body to the pilot burner and another conduit controlled by the bleeder valve for conducting fuel to the main valve control means for operating it in accordance with the movement of the thermostatic element.

2. In combination, a main burner, a fuel supply line, a valve for controlling flow of fuel to said burner, a diaphragm for actuating said valve, said diaphragm having one side thereof connected to said fuel supply line, a pilot burner, a conduit connecting said pilot burner to said supply line, a second conduit connecting said other side of said diaphragm valve to said first conduit, a valve between said conduits, and thermally controlled means connected to said valve and responsive to said pilot burner for controlling flow of fuel from said supply pipe through said conduits to said other side of said diaphragm valve.

3. In combination, a main burner, a fuel supply line, a diaphragm valve for controlling flow of fuel to said burner, the diaphragm of said valve having one side thereof subject to the pressure in said fuel supply line, a conduit connecting the other side of said diaphragm to said supply line, valve means in said conduit for controlling flow of fuel to said other side of said valve, a pilot burner connected to said last named conduit, thermally sensitive means responsive to said pilot burner and directly connected to said valve means for operating said valve means, and means for continuously exhausting a limited quantity of fuel from said other side of said diaphragm valve.

4. In combination, a fuel supply line, a diaphragm valve in said line having one side of the diaphragm thereof maintained under the same pressure as said fuel supply line, a bleeder valve body, a conduit for conducting fuel to said valve body, a second conduit leading from said valve body to the other side of said diaphragm valve for normally maintaining continuous flow of fuel to said other side of said diaphragm, a pilot burner also receiving fuel from said first conduit, a bleeder valve in said valve body between said conduits for shutting off flow of fuel through said second conduit when said burner is ignited, and exhausting means leading from said diaphragm valve to a point adjacent said pilot burner for burning the fuel exhausted from said valve.

5. In combination, a main burner, a pilot burner for said main burner, a fuel supply line, a conduit leading from said line to said pilot burner, a diaphragm valve in said supply line posterior to said conduit and having chambers on opposite sides of the diaphragm of said valve, one of said chambers being in constant communication with said supply line, a conduit leading from said pilot burner to the other chamber, a valve in said conduit, means responsive to operation of said pilot burner for maintaining said

- valve closed during operation of said pilot burner to prevent flow through said conduit, and metered means for exhausting said other chamber to provide for opening of said diaphragm valve when said pilot burner is in operation.
6. In combination, a main burner, a pilot burner for said main burner, a fuel supply line, a first conduit leading from said line to said pilot burner, a diaphragm valve in said supply line posterior to said conduit and having chambers on opposite sides of the diaphragm of said valve, one of said chambers being in constant communication with said supply line, a second conduit leading from said pilot burner to said other chamber, a valve in said second conduit, means responsive to operation of said pilot burner for maintaining said valve closed during operation of said pilot burner to prevent flow through said second conduit, metered means for exhausting said other chamber to provide for opening said diaphragm valve when said pilot burner is in operation, and a temperature limiting control for admitting fuel from said first conduit into said other chamber irrespective of said pilot burner valve when a predetermined temperature has been attained.
7. In combination, a fuel supply line, a main burner, a valve therebetween having inlet and outlet chambers, means for actuating said valve including a diaphragm subjected on one side to the fuel pressure in said inlet chamber, a valve housing, a pilot burner adjacent said main burner and connected to said housing, a conduit leading from said inlet chamber to said housing and therethrough to said pilot burner, a second conduit leading from said housing to the other side of said diaphragm, and thermally sensitive means responsive to the operation of said pilot burner for controlling the flow of fuel through said second conduit to said other side of said diaphragm.
8. In combination, a fuel supply line, a burner, a valve housing in said line and a valve therein controlling fuel flow to said burner, a first conduit leading from the inlet side of said valve housing to a point adjacent said burner, a second conduit leading from said point to a control means for said valve, valve means controlling the flow of fuel from said first conduit through said second conduit, a pilot burner connected to said first conduit anterior to said valve means, and thermally sensitive means supported by said pilot burner and operable only in response to operation of said pilot burner to actuate said valve means.
9. The combination with a heating system including a burner, a fuel supply line therefor, and a diaphragm valve for controlling flow of fuel to said burner, of means for maintaining a pilot flame including a pilot burner head having an air inlet and a fuel inlet, a connection from said fuel inlet to the inlet side of said diaphragm valve including a valve housing, a conduit extending from said housing to the opposite side of said diaphragm valve, valve means in said housing providing for passage of fuel from said pilot burner connection into said conduit, and thermally sensitive means carried by said burner head and responsive to said pilot flame for controlling said valve means.
10. The combination with a heating system including a burner, a fuel supply line therefor, and a diaphragm valve for controlling flow of fuel to said burner, of means for maintaining a pilot flame including a pilot burner head,

a pair of conduits leading to said head, said conduits being connected to opposite sides of the diaphragm of said valve, a chamber providing communication between said conduits, valve means in said chamber, means extending from the inlet side of said valve means for conducting fuel to a pilot burner tip, and thermally sensitive means mounted on said head and operable to control said valve means in response to said pilot flame.

11. In combination, a main burner, a fuel supply line therefor, a diaphragm valve in said line, control means therefor, a pilot burner head for maintaining a pilot flame, a continuously open conduit connected to said line anterior to said valve and supplying fuel to said burner head, a by-pass in said conduit, a second conduit connecting said by-pass to said control means, and thermally sensitive means for controlling said by-pass responsive to the flame at said pilot burner head.

12. In a heating device, a diaphragm valve having two chambers, a fuel supply directly connected to one of said chambers, means for exhausting fuel from the other of said chambers of said valve to cause the valve to open, means for supplying fuel to said other chamber in quantities greater than said fuel is exhausted by said exhausting means, means for cutting off said supply of fuel to said other chamber, and means including a thermostatic element, a pilot burner for heating said element, and valve means directly connected to said thermostatic element for operating the means for cutting off of the supply of fuel to said other chamber.

13. In a heating device, a heater burner, a fuel supply means, a pilot burner, a bleeder valve associated with said pilot burner, a diaphragm valve for controlling the flow of fuel to the heater burner, one chamber of the diaphragm valve being connected directly to the fuel supply means, and the other chamber of said diaphragm valve being connected indirectly to the fuel supply means through the bleeder valve, and thermally sensitive means mounted above said pilot burner and responsive to the flame thereof for controlling the bleeder valve to effect control of said diaphragm valve.

14. In a heating device, a diaphragm valve, means for supplying fuel directly to one side of the diaphragm valve, and a plurality of means for supplying fuel indirectly to the other side of the diaphragm valve to control it, one of said plurality of means including a valve, means for maintaining a pilot flame above said valve, and a thermostat disposed above said flame and having motion transmitting means connected to said valve for operating the valve, another of said plurality of means including a temperature limit control valve, and means for slowly exhausting the fuel which has been indirectly supplied to said diaphragm valve at a constant rate.

15. In a heating device, a diaphragm valve, means for supplying fuel directly to one side of the diaphragm valve, and a plurality of means for supplying fuel indirectly to the other side of the diaphragm valve to control it, one of which means includes a pilot burner, a conduit connected directly between said burner and said first named fuel supply means, a thermostat responsive to said burner, and a valve connected to said thermostat and adapted to be closed when the temperature of the thermostat rises to a predetermined value, and another of said means including a temperature limit control valve adapted

to open when the temperature of the heated space rises to a predetermined value.

16. In a heating device, a combined ignition device and fuel flow device comprising a pilot burner, a thermostatic element adjacent the pilot burner, a valve for by-passing some of the fuel from the pilot burner supply to a pressure actuated fuel supply valve, and means for operating the valve directly connected to said thermostatic element.

17. In a fuel flow control system, a fuel supply line, a main control valve means in said line, a pilot burner for maintaining a pilot flame, a thermostatic element mounted on said burner and responsive to said flame, a bleeder valve body, means connected directly to said fuel supply line for introducing fuel into the bleeder valve body and from the valve body to said pilot burner, a conduit for conveying fuel from the valve body to the main valve control means, a valve in the conduit for controlling flow of fuel therethrough, and means for conveying the motion of the thermostatic element to said valve, said thermostatic element, conveying means and said valve being arranged to bias said valve normally to open position.

18. In an appliance of the character described, the combination of a main burner, a gas supply

line, a diaphragm to control the supply of fuel from said line to said burner, automatically operating means for controlling the pressure of fluid on one side of said diaphragm valve, a pilot burner connected directly with said supply line, means for continuously reducing the pressure on said side of said diaphragm valve, and thermostatically controlled means actuated by said pilot burner and adapted to cut off flow of fluid to said one side of said diaphragm valve for opening said valve.

19. In an appliance of the character described, the combination of a main burner, a gas supply line, a diaphragm valve controlling the supply of fuel from said supply line to said burner, automatically operating means for controlling the pressure on one side of said valve, said means comprising a pilot burner connected to and disposed between said gas supply line, and a conduit connected directly to one side of said valve, thermostatically controlled means actuated by said pilot burner for cutting off flow of fuel to said one side of said diaphragm valve for opening said valve, and a temperature limit control connected to said supply line for increasing the pressure at one side of said diaphragm valve for closing said valve.

HAROLD A. MANTZ.
